Inventor,
G. R. Watson, by
G. C. Kennedy
Attorney.

UNITED STATES PATENT OFFICE.

GEORGE R. WATSON, OF WATERLOO, IOWA, ASSIGNOR TO ARMSTRONG MANUFACTURING COMPANY, OF WATERLOO, IOWA.

DRILL BIT.

Application filed January 2, 1924. Serial No. 684,080.

To all whom it may concern:

Be it known that I, GEORGE R. WATSON, a citizen of the United States of America, and a resident of Waterloo, Black Hawk County, Iowa, have invented certain new and useful Improvements in Drill Bits, of which the following is a specification.

My invention relates to improvements in drill-bits, and the object of my improvement 10 is to supply a bit for drilling holes in rocky strata, which is shaped for most effective service under all the conditions of actual use.

This object I have accomplished by the 15 means which are hereinafter described and claimed, and which are illustrated in the accompanying drawings, in which Figs. 1 and 2 are respectively elevations of the drill and its bit taken at an angle of ninety degrees 20 apart, and Fig. 3 is a plan of the cutting end of the bit.

The drill 1 of cylindrical shape has a coned threaded shank 2 for meshing with the threaded socket of a drill-jar or the 25 like, and the body 3 of the drill has the usual oppositely positioned longitudinal grooves or troughs 5 of semi-cylindrical shape ending terminally at the concave anticlinal axial edge 7.

Opposite sides of the drill are flattened at 30 4 surrounding said troughs 5, and the bit end of the drill is upset at 6 semi-circularly to cause it to conform to the cylindrical drill-hole during the progressive movement 35 of the drill.

The cutting edge of the bit at 9 is a diametrical anticlinal ridge with its faces usually between thirty to forty-five degrees angle relative to the longitudinal axis of the drill, 40 for use in drilling into rock of varying hardness.

The bit 9 projects from sloping anticlinal faces 8 whose angle relative to the axis of the drill is greater than the angle of the 45 faces of the bit 9.

The anticlinal faces 8 serve as crushing faces during the dropping and partial rotation of the drill in use and also serve to limit the penetration of the diametrical bit 50 9 into any cracks or crevices which may at times intersect the bottom of the drill-hole. In the ordinary type of drill-bit where the

bit 9 is longer and has no crushing faces such as the faces 8, the bit edge may enter a crack or crevice to a considerable extent, 55 causing it to chatter or break off relatively large fragments of the rock which pile up and resist crushing and thus hold up and prevent further effective progress of the drill. I have found this to be a great im- 60 pediment in actual practice, but this is entirely obviated when my said improved drill-bit is employed.

In my improved bit, the semicircularly offset marginal parts 6 keep the bit centered 65 in the drill-hole, so that but little rocking movement is required of the drill, and the faces 8 when the drill drops effectually crush the tailings to powder which is swept away upwardly by the water circulation. Relatively large fragments which are broken away by the ordinary bit, as above described, 70 cannot be carried away by the water current, and remain in the bottom of the hole without being crushed by the bit. As the faces 8 are of greater angularity relative to the drill's axis than the faces of the bit ridge 9, a reinforced construction is obtained, and the respective parts are less liable to chip or fracture during use.

Having described my invention, what I 80 claim as new, and desire to secure by Letters Patent, is:

1. A well-drilling tool, comprising an elongated shank having longitudinal grooves 85 on opposite sides meeting at a concave anticlinal edge in the bit-end, said bit-end having oppositely inclined relatively wide crushing faces separated by said grooves and having radial angular straight cutters alined 90 with said concave edge.

2. A well-drilling tool, comprising a shank having longitudinal grooves meeting in a terminal cutting edge, the bit-end having anticlinal crushing faces, and having 95 alined radial depending cutters with anticlinal slopes whose angularity relative to the axis of the tool is different from the angularity of said crushing faces relative to said axis.

Signed at Waterloo, Iowa, this 5th day of Dec., 1923.

GEORGE R. WATSON.
